UNITED STATES PATENT OFFICE.

HARRISON L. HUDSON, OF CHICAGO, ILLINOIS.

GEAR.

1,163,925.

Specification of Letters Patent. Patented Dec. 14, 1915.

Application filed November 30, 1914. Serial No. 874,923.

To all whom it may concern:

Be it known that I, HARRISON L. HUDSON, citizen of the United States, residing at Chicago, in the county of Cook and State of

Illinois, have invented a certain new and useful Improvement in Gears, of which the following is a full, clear, concise, and exact description, reference being had to the accompanying drawings, forming a part of

this specification.

My invention relates to power transmission gears of that class in which the toothed portions are separated from but are movable with respect to the body portions and the invention is of particular service where sound insulating cushioning material is interposed between the toothed and body members of the gears to reduce or eliminate the noise due to gear operation. A gear of

this general class is disclosed by my United States Patent 1,043, 012, dated October 29, 1912, wherein I have shown a plurality of guiding structures each made up of elements included in the formation of a toothed ring and body portion of a gear, whereby these two gear parts are interlocked or interengaged in such a manner as to prevent undesirable circumferential movement between these two gear parts.

The toothed ring of the gear is flexible so that it may be forced out of its true shape when encountering unusual load, and is resilient so that it may automatically resume its true shape when the undue load is removed, the guiding means determining the direction in which the toothed ring may flex when subject to undue load and may return when resuming normal shape.

My present invention has for one of its objects an improved form of guiding structure whereby the parts may more readily be assembled and disassembled and for another of its objects the provision of means for compensating for the contraction of the fibrous, feltlike or other contractible sound deadening material which intervenes between the toothed and body members of the gear so that this sound deadening material may continue to perform its function. I will explain my invention more fully by reference to the accompanying drawings showing the preferred embodiment thereof

as it is embraced in an externally toothed spur gear, though it is to be understood that I do not limit myself to a spur gear, nor to a gear that is externally toothed.

In the drawing Figure 1 is a face view, partially broken away, illustrating one form of the invention; Fig. 2 is a sectional view on line 2-2 of Fig. 1; Fig. 3 is a detail view 60 of a channeled coupling lug entering into the construction; Fig. 4 is a view on line 4-4 of Fig. 2; Fig. 5 is a sectional elevation illustrating a modification; Fig. 6 is a view on line 6-6 of Fig. 5; and Fig. 7 is a sectional elevation illustrating still another modification.

Like parts are indicated by similar characters of reference throughout the different figures.

The body portion 1 of the gear is illustrated as being of skeleton construction and is surrounded by a ring 2 which is provided with gear teeth 3 upon its outer periphery. The ring 2 is flexible so that it may be forced out of its true circular shape and is resilient so that it may automatically resume its proper shape. A composite cushion is interposed between the body 1 and the ring 2, this composite cushion including a sound deadening element 4 which is backed by springs 4¹ (which may be variously formed and arranged) that are depressed by the sound deadening material whereby the springs, due to their own resilience, will press the felt outwardly to maintain it in constant engagement with the inner surface of the ring 2. The springs will follow the sound deadening material 4 as this material contracts so that no space

will intervene between the ring 2 and the sound deadening material 4. The two elements 4, 4¹ of the composite cushion thus co-operate to constitute a sound deadening or insulating element and are together sufficiently resilient to fill the changeable clearance between the gear elements 1 and 2. The cushion will yield to permit the toothed ring to move with respect to the axis of rotation of the body member 1 and transversely of such axis, the clearance between the members 1 and 2 of the gear being preferably just sufficient to permit the gear teeth of another gear that mesh with the

gear teeth 3 to have their outer edges reach the pitch circle of the gear teeth 3, by which arrangement the gears will not become unmeshed although the toothed ring 2 is permitted to move away from the gear with which it is in mesh, when the teeth 3 encounter unusual opposition. In order to prevent undesirable relative circumferential movement of the members 1 and 2, I provide a plurality of insetting coupling lugs 5 that are secured between the insetting flanges 2¹ upon the ring 2 by means of riveting pins 6. These lugs are bottomed upon the inner cylindrical base of the ring 2 on which account the elements 4, 4¹ of the composite cushion are divided into sections or sets that intervene between adjacent lugs 5. These lugs are provided with insetting channels 7 located transversely of the plane of the gear. There are desirably three such lugs spaced equidistant around the gear. Each channel or recess 7 receives a radially disposed or alined coupling block 8 that is in free sliding fit with the channel side walls which thus coöperate with the engaging block 8 to prevent undesirable circumferential movement relatively between the members 1 and 2 of the gear. The three coupling blocks are rigidly secured, by means of riveting pins 9, between the spaced apart rings or wall portions 10 that constitute portions of the body member 1, the coupling blocks thus being in fixed relation to the center of the body gear member 1. Sufficient clearance normally intervenes between the outer surfaces of the coupling blocks 8 and the bottoms of the channels 7 to permit of the desired relative movement between the ring and body members of the gear.

When the composite cushion composed of the elements 4, 4¹ is compressed consequent upon relative movement between the ring and body members of the gear, the coupling lugs 5 will move radially of the gear, being guided in their radial movement by the radially disposed or alined guiding blocks 8. The clearance between the bottoms of the channels 7 and the outermost faces of the blocks 8 permits the lugs 5 to slide toward the axis of rotation of the gear as these lugs become interposed between the place of unusual pressure upon the teeth 3 and the shaft 11 upon which the body portion of the gear is keyed. The toothed ring being sufficiently flexible, the portion thereof that is immediately subject to unusual pressure or load is moved toward the body of the gear without accompanying undesirable circumferential motion owing to the guide structure which I have provided. When the unusual load has been removed the ring will automatically resume its proper shape due to resiliency. Separation of the members 1 and 2 of the gear longitudinally of the axis

is prevented because of the interposition of the insetting lugs 5 between the ring portions 10 of the body member 2 that engage the end faces of the lugs (these faces are parallel with the faces of the gear and included in the plane of rotation of the gear), the gear structure being further strengthened at the localities of said lugs by the webs 12 that form, with the walls 10, radially disposed pockets in which the lugs 5 may reciprocate. Holes 13 are passed through the ring 2 where the lugs 5 are located so that the members of the gear may readily be separated, after the pins 6 and 9 are removed, by means of a punch that may be passed through the holes 13 to drive the lugs 5 and blocks 8 into the pockets formed by the webs 12 and the wall rings 10, these pockets being sufficiently deep to permit the lugs 5 to be driven so far to the center as to clear the flanges 2¹, whereafter the gear members may be slid apart. The inner circumferential surfaces of the sound deadening portions of the composite cushion are provided with metallic backing plates 14 to prevent the coil springs from injuring the sound deadening material.

While I have herein shown and particularly described the preferred embodiment of my invention I do not wish to be limited to the precise details of construction shown as changes may readily be made without departing from the spirit of my invention, but

Having thus described my invention I claim as new and desire to secure by Letters Patent the following:—

1. A gear including spaced apart toothed and body portions that are relatively movable transversely of the axis of rotation; and a guide structure having complemental portions that are provided upon said gear portions for defining the relative movement between said gear portions transversely of the axis of rotation and which guide structure portions are in the form of displaceable interengaging coupling lugs and coupling blocks.

2. A gear including spaced apart toothed and body members; and a guide structure having complemental portions that are provided upon said members, and which guide structure serves to define relative movement between said members transversely of the axis of rotation, the toothed member of the gear being of ring like formation and sufficiently flexible to permit it to be moved with respect to the body member of the gear at the part where unusual load is encountered and being sufficiently resilient to permit it to resume its proper shape when the undue load is removed, the aforesaid guide structure portions being in the form of coupling lugs and coupling blocks in sliding fit with said lugs, there being sufficient clear-

ance to permit of the flexible movement of the ring member of the gear.

3. A gear including spaced apart toothed and body members; and a guide structure having complemental portions that are provided upon said members, and which guide structure serves to define relative movement between said members transversely of the axis of rotation, the toothed member of the gear being of ring like formation and sufficiently flexible to permit it to be moved with respect to the body member of the gear at the part where unusual load is encountered and being sufficiently resilient to permit it to resume its proper shape when the undue load is removed, the aforesaid guide structure portions being in the form of insetting coupling lugs having channels upon their inner ends extending transversely of the plane of the gear and carried by the ring member of the gear and coupling blocks carried by the body member of the gear and in sliding fit with said lugs, sufficient clearance intervening between the bottoms of the channels and the outermost faces of said blocks to permit of the flexible movement of the ring member of the gear and the accompanying movement of the coupling lugs carried thereby, the body member of the gear having portions which engage end faces of the coupling lugs to prevent longitudinal displacement of the gear members.

4. A gear including spaced apart toothed and body members relatively movable in the plane of the gear; and a composite cushion interposed between these gear members, a portion of this cushion being in the form of a body of sound deadening material engaging one of the members and a spring element in engagement with this sound deadening material and the other gear member.

5. A gear including spaced apart toothed and body members; and a guide structure having complemental portions that are provided upon said members, and which guide structure serves to define relative movement between said members transversely of the axis of rotation, the toothed member of the gear being of ring like formation and sufficiently flexible to permit it to be moved with respect to the body member of the gear at the part where unusual load is encountered and being sufficiently resilient to permit it to resume its proper shape when the undue load is removed, the aforesaid guide structure portions being in the form of insetting coupling lugs having channels upon their inner ends extending transversely of the plane of the gear and carried by the ring member of the gear and coupling blocks carried by the body member of the gear and in sliding fit with said lugs, sufficient clearance intervening between the bottoms of the channels and the outermost faces of said

blocks to permit of the flexible movement of the ring member of the gear and the accompanying movement of the coupling lugs carried thereby, the body member of the gear having spaced apart wall portions 10 70 into the spacing between which the insetting lugs project to prevent longitudinal displacement of the toothed and body members of the gear.

6. A gear including spaced apart toothed and body members; and a guide structure having complemental portions that are provided upon said members, and which guide structure serves to define relative movement between said members transversely of the axis of rotation, the toothed member of the gear being of ring like formation and sufficiently flexible to permit it to be moved with respect to the bcdy member of the gear at the part where unusual load is encountered 85 and being sufficiently resilient to permit it to resume its proper shape when the undue load is removed, the aforesaid guide structure portions being in the form of insetting coupling lugs having channels upon their inner ends extending transversely of the plane of the gear and carried by the ring member of the gear and coupling blocks carried by the body member of the gear and in sliding fit with said lugs, sufficient clearance intervening between the bottoms of the channels and the outermost faces of said blocks to permit of the flexible movement of the ring member of the gear and the accompanying movement of the coupling lugs 90 carried thereby, the body member of the gear having spaced apart wall portions 10 into the spacing between which the insetting lugs project to prevent longitudinal displacement of the toothed and body members of the gear, there being also webs 12 which coöperate with the wall portions 10 in defining pockets in which the lugs reciprocate and which pockets are sufficiently deep to permit the lugs, when removed, to be received 100 fully therein.

7. A gear including spaced apart toothed and body members; and a guide structure having complemental portions that are provided upon said members, and which guide structure serves to define relative movement between said members transversely of the axis of rotation, the toothed member of the gear being of ring like formation and sufficiently flexible to permit it to be moved with respect to the body member of the gear at the part where unusual load is encountered and being sufficiently resilient to permit it to resume its proper shape when the undue load is removed, the aforesaid guide structure being in the form of insetting coupling lugs carried by the ring member of the gear and coupling blocks carried by the body member of the gear and in sliding fit with the lugs, there being freedom for sufficient 115 120 125 130

relative movement between the lugs and blocks to permit of the flexible movement of the ring member of the gear and the accompanying movement of the coupling lugs carried thereby, the body member of the gear having spaced apart wall portions 10 into the spacing between which the insetting lugs project to prevent longitudinal displacement of the toothed and body members of the gear.

8. A gear including spaced apart toothed and body members; and a guide structure having complementary portions that are provided upon said members, and which guide structure serves to define relative movement between said members transversely of the axis of rotation, the toothed member of the gear being of ring like formation and sufficiently flexible to permit it to be moved with respect to the body member of the gear at the part where unusual load is encountered and being sufficiently resilient to permit it to resume its proper shape when the undue load is removed, the aforesaid guide structure being in the form of insetting coupling lugs carried by the ring member of the gear and coupling blocks carried by the body member of the gear and in sliding fit with the lugs, there being freedom for sufficient relative movement between the lugs and blocks to permit of the flexible movement of the ring member of the gear and the accompanying movement of the coupling lugs carried thereby, the body member of the gear having spaced apart wall portions 10 into the spacing between which the insetting lugs project to prevent longitudinal displacement of the toothed and body members of the gear, there being also webs 12 which co-operate with the wall portions 10 in defining pockets in which the lugs reciprocate and which pockets are sufficiently deep to permit the lugs, when removed, to be received fully therein.

9. A gear including spaced apart toothed and body members; and a guide structure having complementary portions that are provided upon said members, and which guide structure serves to define relative movement between said members transversely of the axis of rotation, the toothed member of the gear being of a ring like formation and sufficiently flexible to permit it to be moved with respect to the body member of the gear at the part where unusual load is encountered and being sufficiently resilient to permit it to resume its proper shape when the undue load is removed, the aforesaid guide structure portions being in the form of insetting coupling lugs having channels upon their inner ends extending transversely of the plane of the gear and carried by the ring member of the gear and coupling blocks carried by the body member of the gear and in sliding

fit with said lugs, sufficient clearance intervening between the bottoms of the channels and the outermost faces of said blocks to permit of the flexible movement of the ring member of the gear and the accompanying movement of the coupling lugs carried thereby, said toothed and body members each having portions between which the coupling lugs are interposed and which engage the end faces of such coupling lugs to prevent longitudinal separation of the gear members.

10. A gear including spaced apart toothed and body members; and a guide structure having complementary portions that are provided upon said members, and which guide structure serves to define relative movement between said members transversely of the axis of rotation, the toothed member of the gear being of ring like formation and sufficiently flexible to permit it to be moved with respect to the body member of the gear at the part where unusual load is encountered and being sufficiently resilient to permit it to resume its proper shape when the undue load is removed, the aforesaid guide structure portions being in the form of insetting coupling lugs having channels upon their inner ends extending transversely of the plane of the gear and carried by the ring member of the gear and coupling blocks carried by the body member of the gear and in sliding fit with said lugs, sufficient clearance intervening between the bottoms of the channels and the outermost faces of said blocks to permit of the flexible movement of the ring member of the gear and the accompanying movement of the coupling lugs carried thereby.

11. A gear including spaced apart toothed and body portions that are relatively movable transversely of the axis of rotation; and a guide structure having complementary portions that are provided upon said gear portions for defining the relative movement between said gear portions transversely of the axis of rotation and which guide structure portions are in the form of channeled coupling lugs and coupling blocks entering the channels of the lugs.

12. A gear including spaced apart toothed and body portions that are relatively movable transversely of the axis of rotation; and a guide structure having complementary portions that are provided upon said gear portions for defining the relative movement between said gear portions transversely of the axis of rotation and which guide structure portions are in the form of displaceable interengaging coupling lugs and coupling blocks, some of said guide structure portions being channeled to receive guide structure portions complementary thereto.

13. A gear including spaced apart toothed and body portions that are relatively movable transversely of the axis of rotation; and

a guide structure having complemental portions that are provided upon said gear portions for defining the relative movement between said gear portions transversely of the
5 axis of rotation, one of said guide structure portions being removably mounted upon the gear portion carrying it.

In witness whereof, I hereunto subscribe my name this 19th day of November A. D., 1914.

HARRISON L. HUDSON.
